COLLAPSIBLE CROWN BLOCK

John W. MacClatchie, Los Angeles, Calif., assignor to MacClatchie Manufacturing Company of California, Compton, Calif., a corporation of California

Application December 4, 1940, Serial No. 368,482

3 Claims.

(Cl. 254—190)

My invention relates to collapsible crown blocks for oil well derricks and the like.

A crown block is mounted on the water table of a derrick and provided with a number of sheaves over which the cable line is reeved for supporting the traveling block. The present oil well production practice is to allow the crown block to remain on the water table during the entire time that the well is on production, even though the crown block is only used at infrequent intervals. This is due to the fact that present day crown blocks must be disassembled in order to pass through the opening in the water table of a derrick and must then be reassembled before use.

The object of my invention is to provide a collapsible crown block which may be easily and quickly mounted on the water table as a unit in order to make it practical to raise a crown block into position on the water table whenever the use of a crown block is required and to remove the crown block after the work has been completed, rather than to allow the crown block to remain on the water table during the entire period that the well is on production.

Another object of my invention is to provide a crown block in which the cable line is adapted to be reeved around the sheaves of the crown block and the sheaves of the traveling block before the crown block is raised into position in the derrick.

Another object of my invention is to provide a collapsible sheave supporting member which in collapsed or retracted position is adapted to pass through the opening in the water table of a derrick and which in extended position is adapted to extend across said opening in the water table.

Another object of my invention is to provide a collapsible crown block which may be mounted into position in the derrick without first disassembling the crown block, and then reassembling the crown block after the parts have been raised into position in the derrick.

Another object of my invention is to provide a collapsible crown block in which the cable lines may be reeved around the sheaves of the crown block and the sheaves of the traveling block before the crown block is raised into position in the derrick, so that the crown block in collapsed position with the cable lines reeved around the sheaves may be raised through the opening in the water table, after which the crown block is adjusted to extended position, and lowered on the water table with the crown block and the cable line ready for use.

Although my invention relates primarily to crown blocks for use in connection with producing wells, the invention may be used in connection with crown blocks for use in the drilling of wells.

My invention has many other objects, advantages, and features, some of which, with the foregoing, will be set forth at length in the following description where I shall describe certain forms of my invention for use in connection with producing wells, which I have selected for illustration in the drawings accompanying and forming a part of the present specification.

Referring to the drawings:

Figure 1 is a plan view showing the crown block in retracted position coming up through the water table opening.

Figure 2 is a plan view showing the crown block in extended position and in place on the water table.

Figure 3 is a side elevation of the collapsible crown block in extended position in place on the water table, with the retracted position indicated on dotted lines.

Figure 4 is a section taken on the line 4—4 of Figure 3.

Figure 5 is a side elevation of a hinged crown block in position for use on the water table, with the collapsed position shown in dotted lines.

Figure 6 is a section taken on the line 6—6 of Figure 5.

In the drawings the numeral 10 indicates an opening in a water table 11 at the top of a derrick 12. The water table is formed by water table beams 13 and 14, around which beams is usually a working platform (not shown). The opening 10 is square in the usual derrick. The water table beams 13 provide a support for the crown block.

In the form of my invention shown in Figures 1—4 inclusive, the crown block comprises supporting members 15 which are adapted to be extended and retracted longitudinally and sheaves 16 mounted on said supporting members. Any number of sheaves may be mounted on the supporting members 15 in the usual manner, that is, on bearings and with means for readily adjusting the position of the sheaves on the supporting members.

As shown in Figures 1—4, the supporting member 15 may comprise I-beams 17, 18 and 19, connected together with I-beam spacers 20, extensible and retractable members 21 and supporting blocks 22. The extensible and retractable members 21 are secured to the beams

17 and 19. Said members 21 are shown in extended position in Figures 2 and 3 and in retracted position in Figure 1 and in dotted lines in Figure 3.

Means are also provided to limit the outward movement of the extensible members 21. An instance of this arrangement is shown in Figures 3 and 4 in which the extensible members 21 are provided with longitudinal slots 23, and bolts 24 are inserted through said slots 23 and holes in the beams 17 and 19, the outward movement of said extensible members 21 being limited by the engagement of the inner ends of said longitudinal slots 23 with said bolts 24.

The operation of the collapsible crown block of my invention is as follows:

Before the crown block is raised into position on the water table beam 13, a cable line 25 from usual hoisting drum (not shown) may be reeved around the sheaves 16 and the sheaves of a usual traveling block 25a, and the other so-called "dead-end" of said cable line secured at the base of the derrick in any usual manner (not shown).

The extensible members 21 are moved into retracted position. The crown block is then raised through the water-table opening 10 by means of a cable line supported by the usual gin, sole or in any other manner. The extensible members 21 are then moved to extended position as shown in Figures 2 and 3 and the crown block is lowered on the water table beams 13, after which the cable line 25 is ready for use.

Obviously, the crown block may be raised into position without the cable line 25 reeved around the sheaves 16, and the cable line 25 reeved around said sheaves 16 and the sheaves of the traveling block 25a after the crown block is in position on the water table beams 13.

Obviously, instead of securing the so-called "dead line" of the cable line 25 at the base of the derrick, said end of said cable line 25 may be secured to the traveling block 25a, which is frequently done in present day practice.

In the modification of my invention shown in Figures 5 and 6, the sheaves 16 are mounted on beams 30 and 31 which are hinged together by means of a hinge plate 32 mounted on a hinge pin 33.

The beam 30, which may be in the form of an I-beam as shown in the Figures 5 and 6, is bored to take the reduced shank 34 of the hinge pin 33, and the hinge plate 32 is bored to receive an enlarged portion 35 of said pin.

The construction of the remainder of this modification, the use and operation of said crown

block are deemed to be apparent from the description set forth herein in connection with the form of the invention shown in Figs. 1-4, inclusive, and will therefore not be set forth herein.

From the foregoing description taken in connection with the accompanying drawings, the uses, advantages, and operation of my invention will be readily understood by those skilled in the art to which the invention appertains. While I have described the forms of my invention which I now consider to be the best embodiments thereof, I desire to have it understood that the forms shown are merely illustrative and that the invention is not to be limited to the details disclosed herein, but is to be accorded the full scope of the appended claims.

I claim:

1. A crown block structure adapted to be positioned on top of the water table of a derrick comprising a plurality of sheaves, means for supporting said sheaves, said means comprising a plurality of parts movable with respect to each other from an extended position in line with each other to a collapsed position, said parts in collapsed position enabling said means to be moved through the water table and in extended position enabling said means to overlie the water table.

2. A crown block structure adapted to be positioned on top of the water table of a derrick comprising a plurality of sheaves, means for supporting said sheaves, said means comprising a plurality of parts movable with respect to each other from an extended position in line with each other to a collapsed position, said parts in collapsed position enabling said means to be moved through the water table and in extended position enabling said means to overlie the water table.

30 3. A crown block structure adapted to be positioned on top of the water table of a derrick comprising a plurality of sheaves, means for supporting said sheaves, said means comprising a plurality of parts movable with respect to each other from an extended position in line with each other to a collapsed position, said parts in collapsed position enabling said means to be moved through the water table and in extended position enabling said means to overlie the water table, and a cable line reeved around said sheaves of said crown block before said crown block is raised into position on said derrick.

35 4. A crown block structure adapted to be positioned on top of the water table of a derrick comprising a plurality of sheaves, means for supporting said sheaves, said means comprising a plurality of parts movable with respect to each other from an extended position in line with each other to a collapsed position, said parts in collapsed position enabling said means to be moved through the water table and in extended position enabling said means to overlie the water table, and a cable line reeved around said sheaves of said crown block and the sheaves of a travelling block before said crown block is raised into position on said water table.

JOHN W. MacCLATCHIE.
